(57) **CLAIM**

The ornamental design for a portable structure as shown and described.

DESCRIPTION

FIG. 1 is a front perspective view of a portable structure, with the doors shown in a closed position, showing my new design.

FIG. 2 is a top perspective view thereof.

FIG. 3 is a first left side elevation view thereof.

FIG. 4 is a right side elevation view thereof.

FIG. 5 is a front elevation view thereof.

FIG. 6 is a rear elevation view thereof.

FIG. 7 is a top plan view thereof.

FIG. 8 is a bottom plan view thereof.

FIG. 9 is a front perspective view thereof, with the doors shown in an open position.

FIG. 10 is a top perspective view thereof; and,

FIG. 11 is a front elevation view thereof.

The broken lines in the figures are for the purpose of illustrating environmental matter as well as portions of the portable structure that form no part of the claimed design.

1 Claim, 9 Drawing Sheets
